SAFETY SWITCH

Francis J. Battestin and Earl C. Fox,
Coshocton, Ohio

Application March 24, 1939, Serial No. 263,999

5 Claims. (Cl. 200—52)

This invention relates to safety switches for airplanes, automobiles and other vehicles propelled by engines having ignition systems; and the general object of the invention is to provide a switch which will automatically cut off the ignition, thereby to stop the engine, the instant a collision occurs. The device of the invention is also operative to cut off the ignition if the automobile should turn over or be brought to a very sudden stop, that is, a stop more sudden than would occur in normal traffic. The general result of use of the safety switch will be to decrease the loss of life and property from fire, resulting from accidents to airplanes, automobiles etc.

15 In the accompanying drawing showing a preferred embodiment of the invention:

Fig. 1 is a vertical, longitudinal, sectional view of the device, the ignition circuit being omitted, because well known; and

20 Fig. 2 is a vertical cross section.

Referring particularly to the drawing, there is shown a box or casing 5 having a lid 6 and providing a housing for supporting and protecting the several parts of the safety switch. Within the 25 casing or box are two switches 7 whose particular construction forms no part of the present invention and hence is not shown, each of said switches being placed in the ignition circuit of the vehicle, wires 8 being provided for this purpose. Preferably the switches 7 are rigidly secured to the bottom of the casing 5 adjacent either end. It will be understood that the switches are arranged in series with each other and with the ignition circuit so that if either switch is open the ignition 30 circuit will be broken.

35 Each of the switches 7 has a switch lever 9 arranged to extend upwardly from the switch casing, each of the switch levers 9 normally being held in circuit-closing positions by means of a coil spring 10 connected at one end to the upper end of the switch lever and connected at the other end to a screw 11. Each screw 11 is passed through an aperture 12 in an end wall of the box or casing and a thumb screw 13 is threaded on each screw 11 and bears against the outside of the 40 end wall, thereby to draw up the screw 11 and impose an adjustable tension on the coil spring 10, which in turn holds the switch lever 9 with greater or less tension in closed position. Normally, therefore, the ignition circuit would be 45 maintained.

50 Located preferably centrally of the box or casing 5 is a heavy weight 14 which may be of lead or lead alloy, said weight having adjustable hooks 55 15 at each end with which it may be connected to

a pair of wires or cables 16 extending to and connected with switch levers 9. Apertures 17 may be provided intermediate the ends of the switch levers to facilitate such connection. It will be clear that the tension of the two coil springs 5 10 serves not only to hold the switches in closed position but will maintain the wires or cables 16 taut and practically horizontal, with the weight 14 thus held in the middle of the box, free to move in any direction in response to its momentum or inertia. A sufficiently strong force will overcome the powerful pull of the two coil springs 10 and will move the switch levers 9 to open position shown in dotted lines. Preferably the switches 15 7 are toggle switches which are so made that when the switch levers are moved to open position they will remain in that position, thus requiring re-setting of the device, which is easily effected by taking off the lid 6 and moving the switch levers 9 back into the circuit-closing positions. 20

25 A particular advantage of the described construction is the fact that the device will operate regardless of the direction in which the blow comes, a sidewise collision or over-turning of the car being just as effective as an endwise collision. Another advantage is the ease with which the device may be installed: it is only necessary to 30 secure the box under the hood of a car or at some other appropriate point and make the necessary connections with the ignition circuit. The device requires no attention except after a collision or other accident opening the ignition circuit. A further advantage is the fact that the 35 device may be sold at a very low cost. There is nothing in the construction which can get out of order and hence the safety switch of this invention is good for the life of the car or other vehicle to which it may be attached.

40 Obviously the present invention may be embodied in a number of forms neither shown nor described but within the scope of the appended claims.

45 Having described an embodiment of the invention, what we claim as new and desire to secure by Letters Patent is:

1. A safety device of the character described comprising, in combination, a casing; a pair of switches in the casing having operating levers extending outwardly therefrom; a weight; a pair of flexible members each connected at one end to 50 an operating lever and at the other end to the weight; a pair of coil springs connected to the operating levers; and means to adjust the tension of the coil springs; the parts being so arranged and constructed that the coil springs hold the 55

- switches closed and the two flexible members taut, with the weight between them free to move in any direction if acted upon by forces sufficient to overcome the tension of either spring.
5. 2. The invention according to claim 1, wherein the two switches are in series with each other and are in the ignition circuit of an internal combustion engine.
3. A safety device comprising, in combination, 10 a switch adapted when open to break the ignition circuit of an engine; a spring holding the switch closed; and a weight flexibly mounted and connected to the switch and partly supported by the spring tension, said weight opening the switch 15 when its inertia or momentum exceeds the tension of the spring.
4. The invention according to claim 3, wherein there is adjustable means connected to the switch and also to the spring, and adapted to regulate the tension of the spring and also to reset the switch after the latter breaks the ignition circuit.
5. The invention according to claim 1, wherein the means to adjust the tension of the coil springs comprise a pair of threaded members each passing through a wall of the casing and having 10 a nut outside the casing which draws up the threaded member; said threaded members each being attached to an operating lever to permit resetting of the switches from outside of the casing.
